SETTING GAUGE FOR SETTING REVOLVABLE EMERY GRINDER ROLLERS

James Dronsfield, Oldham, England

Application August 31, 1938, Serial No. 227,605
In Great Britain March 19, 1938

4 Claims. (Cl. 33—185)

These improvements relate to a micrometer setting gauge for use in setting revolvble emery grinder discs with respect to card wire used to clothe the main cylinder, doffer, or other wire covered rollers or devices used in carding engines or other apparatus.

The gauge is of simple character and is distinguished in that same can be applied or used with respect to an emery grinder disc in ready fashion, and after application and manipulation, the same can be set with accuracy to graduations and the emery grinder disc thereafter adjusted with respect to the wire on the cylinder, doffer or the like to the exact degree conforming to the graduated setting. Further, the general arrangement or combination of parts has some novelty as a whole for the purpose stated.

The accompanying drawing illustrates the invention, and, in such drawing:

20 Fig. 1 is a front view of the micrometer setting gauge.

Fig. 2 shows a section taken at right-angles on the line II—II, Fig. 1.

Fig. 3 is an end elevation.

25 Fig. 4 shows a section at right-angles of Fig. 2, taken on the line IV—IV.

Fig. 5 is a section of Fig. 3, taken on the line V—V.

Fig. 6 shows a plan of Fig. 3.

30 The gauge has a body portion *a* conveniently segmental with combined or off-set boss *a*², and the inner face *a*¹ of the body portion may be curved or shaped and carefully machined to conform to or so as when applied to bear upon or 35 contact with the shell of the grinder tube on which the emery grinder disc revolves and traverses, and which is indicated by the dotted line *t* in Fig. 3.

The off-set boss *a*² is bored and the upper part 40 of the bore has a screw-thread *a*³ the major or lower part of the bore being plain as shown (see Figs. 2 and 4). In such boss fits a cylindrical socket *b*, the upper cylindrical part thereof having a screw-thread *b*³ whilst the lower part is plain. A reduced annular recess *b*¹ lies intermediate of the screw-threaded portion *b*³ and the plain portion so that a screw-threaded pinching stud *c* may, when necessary, lock any adjustment of the cylindrical socket *b*. The cylindrical socket *b* is centrally bored but not right through, to produce a cup-like cavity *b*² for a plunger *d* conveniently cylindrical and which is shown as having a rounded top *d*¹. A spiral spring *d*² fits between the bottom of the cup-like cavity *b*² and the bored inner end of the cylindrical plunger 55

d and this spring *d*² tends to press the cylindrical plunger *d* outwards.

There is a lateral arcuate elongated slot *a*⁴ in the off-set boss *a*², and a long screwed stud *e* is screwed through the wall of the cylindrical socket *b* and the inner end of this long screwed stud *e* engages an elongated vertical sunk slot or recess *b*⁴ in the cylindrical plunger *d*. If this long screwed stud *e* be moved angularly it will (within the limits of the lateral elongated slot *a*⁴) turn the cylindrical socket *b* and the cylindrical plunger *d*. Consequently, by inscribing a mark such as an arrow tip *g* on one element, conveniently the element *b*, and graduations *h* on the other element and conveniently the upper face of the element *a*² (see Fig. 6), the amount of relative movement made is denoted or indicated. Use is made of this for the desired accurate setting of the gauge.

Off-set from the bored boss *a*² is a further 20 bored guide socket *a*⁵. There is also provided a machined bridge-plate *i* which has a round or shaped shank *i*¹ and this shank fits in the bore of the last mentioned guide socket *a*⁵.

Before using the described gauge, the cylindrical socket *b* is initially set by turning the long 25 screwed stud *e* to place the arrow tip *g* opposite zero on the graduated scale *h*, Fig. 6, this action tending to slightly advance or move outwards the cylindrical socket *b*. Thereafter, and with all the parts properly disposed, the body *a* is applied so as to contact with the tube *t* of the emery grinder disc, and with the long screwed stud *e* not binding the cylindrical plunger *d*, the spring *d*² pushes said plunger *d* outwards. The bridge plate *i* has its shank *i*¹ in the bore of the guide socket *a*⁵, and the bridge plate *i* is disposed as to its machined under face of one limb over the emery grinder disc, whilst the under face of the other limb bears on the rounded end *d*¹ of the cylindrical plunger *d*. When the machined bridge plate *i* is pressed down onto the surface of the emery grinder disc, this act will also press down the cylindrical plunger *d* against the action of the spring *d*², thus bringing the rounded extremity *d*¹ of said cylindrical plunger *d* into absolute alignment with the periphery of the emery grinder disc.

In this condition the long screwed stud *e* is 40 screwed-up to jam the cylindrical plunger *d*. The bridge plate *i* is then removed from the gauge.

To set the gauge to the desired degree, the long 45 screwed stud *e* is moved angularly in the lateral slot *a*⁴ the required number of degrees from the zero mark 0 (say 3 degrees representing three one- 50

thousandths) the degrees being read on the graduations or index h . This gives the known desired accurate adjustment, the cylindrical plunger d being retracted three one-thousandths with respect to the off-set boss a^2 . The user secures the adjustment by clamping with the screw-threaded pinching stud c so as to firmly bind the cylindrical socket b against accidental interference.

Having set the gauge to the known degree, the 10 workman applies and uses the gauge in turn with respect to each end of the grinder tube t of the emery grinder disc and he then sets the emery grinder disc in (by adjusting the support brackets at each end) until the rounded end d^1 of the 15 cylindrical plunger d presses on the wire of the cylinder, doffer or the like. Thus, if the adjustment is $\frac{1}{1000}$ of an inch the emery grinder disc is set in to that extent (by trial at each end of the tube t) and will on operation remove that length 20 from the wire.

The graduations may be, as shown at Fig. 6, by 25 marks from 0 to 7, or as may be required, and so if each mark represents $\frac{1}{1000}$ of an inch any adjustment within the limits of the lateral slot a^4 for the long screwed stud e can be obtained according to the graduations.

I declare that what I claim is:

1. A micrometer setting gauge for the indicated purposes comprising a body portion adapted to bear on the grinder tube, a bored off-set boss, a cylindrical socket fitting said boss, screw-threads on said boss and on said cylindrical socket, graduation markings with respect to said boss and said socket, a movable plunger fitting said cylindrical socket, a spring device acting on said movable plunger, a screwed device adapted to engage said cylindrical socket and said movable plunger, said screwed device being angularly movable in a slot in the off-set boss, a guide socket in connection with the body portion of the gauge and a removable bridge plate with shank adapted to fit said guide socket and to co-operate with the movable plunger and the emery grinder disc.

2. A micrometer setting gauge for the indicated 45 purposes comprising a body portion adapted to bear on the grinder tube, a bored off-set boss, a cylindrical socket fitting said boss, screw-threads at the upper end of said boss and at the upper end of said cylindrical socket, co-operating grad-

uation marks in connection with said boss and said socket, a movable plunger with elongated slot, said plunger fitting the cylindrical socket, a spring acting on said plunger, a screwed device adapted to engage said cylindrical socket and said movable plunger and capable of angular movement in a slot in the off-set boss, a guide socket on the body portion of the gauge structure, and a removable bridge plate with shank adapted to fit said guide socket and to co-operate with the movable plunger and the emery grinder disc.

3. A micrometer setting gauge for the indicated purposes comprising a body portion, a bored off-set boss, a cylindrical socket fitting said boss, screw-threads on said boss and on said cylindrical socket, graduation markings with respect to said boss and said socket, a movable plunger fitting said cylindrical socket, a spring contrivance acting on said movable plunger, a screwed device engaging said cylindrical socket and said movable plunger, a lateral slot in the bored off-set boss, said screwed device being angularly movable in said slot, a guide socket in connection with the body portion of the gauge, and a removable bridge plate with shank adapted to fit said guide socket and to co-operate with the movable plunger and the emery grinder disc and means to lock the cylindrical socket when the required adjustment thereof has been made.

4. A micrometer setting gauge for the indicated 30 purposes including a body portion, a bored off-set boss, a cylindrical socket fitting said boss, screw-threads on said boss and on said cylindrical socket, graduation markings with respect to said boss and said socket, a movable plunger guided 35 in the cylindrical socket, a spring device acting on said movable plunger, an elongated slot in said movable plunger, a screwed stud engaging said cylindrical socket and the slot in said plunger, an arcuate slot in the bored off-set boss, in which 40 said screwed stud is angularly movable, a guide socket on the gauge body adjacent the bored off-set boss, and a removable bridge plate with shank adapted to fit said guide socket and to co-operate with the movable plunger and the emery 45 grinder disc, a groove around the cylindrical socket and a screwed stud to lock same when the required adjustment of same has been made.

JAMES DRONSFIELD.
